APPARATUS FOR PROCESSING TUBULAR
METAL WORKPIECES

Robert U. Geib, Jr., Edgewood, Pa.

Application October 9, 1933, Serial No. 692,876

4 Claims. (Cl. 80—13)

This invention relates to the manufacture of seamless pipes and tubes from solid rounds, or "billets", and to any and all of the operations used therein, such as "piercing", "expanding", "elongating", "reducing", etc., and any combination thereof.

In the past, considerable difficulty has been experienced in obtaining flawless products from the power actuated metal-working rolls of seamless pipe and tube mills. The processing of the metal of the billet, or work-piece, must be carefully controlled, otherwise "upsetting" will occur, or grooves and ridges, annular bulging, tearing, uneven wall thickness, etc., will appear in the product.

In addition, a great many other difficulties and limitations are encountered, such as the inability of the metal-working rolls to effect the desired amount of processing without resorting to numerous subsequent operations, difficulty in obtaining maximum speed of production, and the tendency of most metal-working rolls to draw metal into the inlet of the metal pass at a considerably greater rate of speed than that at which it is expelled from the outlet.

A number of rather late developments tend to overcome a great many of the difficulties and limitations referred to, and also increase to a great degree the speed of production of all types of seamless pipe and tube mills. According to these new principles, the conventional stationary work-piece guides are superseded by power-actuated grooved rolls rotating on axes substantially at right angles to the pass defined by the metal-working rolls of the mill, and each having a peripheral velocity in the direction of and, greater than, the longitudinal travel of a work-piece progressing therethrough.

The effect of these power-actuated guide rolls is to lower the usual resistance to rotation of the work-piece offered by the stationary guides, and to greatly assist the longitudinal travel thereof. In its final analysis, the power-actuated guide rolls serve to divert longitudinally the peripheral flow of the metal of the work-piece which is occasioned by the metal-working rolls. In order to accomplish this result to any degree of satisfaction, the guide rolls should cause a tension, or at least materially reduce the compression, of the metal in those portions of the pass wherein the most part of the processing is done.

The conventional disposition of these guide rolls was with their closest contact surfaces at the "gorge", or most constricted portion of the pass defined by the metal working rolls. In this

position, they permitted too much distortion, or "ovality", in the outlet end of the pass, with the result that the metal of the work-piece was diverted from a tangential to a longitudinal direction in any improper manner, or degree. Under these conditions the diameter of the work-piece could not be controlled.

Even more recent developments have taught that the guide rolls should be disposed with their contact surfaces in the outlet end of the pass, for the reason that the metal of the work-piece displaced by the guide rolls will be free in this section to move in a longitudinal direction.

When the metal of the work-piece is extremely plastic, due to unusually good heating, it will, of course, offer very little resistance to displacement. Therefore, advantage could be taken of this fact by disposing the contact surfaces of the guide rolls even farther in the outlet end of the pass. However, this highly desirable condition of metal is not constantly encountered in successive work-pieces. It is also a fact that this condition is not constant in a single work-piece.

If the metal of the work-piece is not unusually plastic, due to insufficient heating, the guide roll contact surfaces should still be disposed in the outlet end of the pass, but at a point more adjacent the "gorge" of the metal-working rolls, in order to more effectively limit distortion which, in this condition, cannot be easily displaced from a point adjacent the extreme outlet of the pass.

In order to cope with these varying conditions, it has been deemed most expedient, and even necessary, to dispose the contact surfaces of the guide rolls in a predetermined "mean" position in the outlet end of the pass.

In the present invention, advantage is taken of the condition of the metal of the work-piece in such manner as to assure the exactly proper positioning of the contact surfaces of the guide rolls.

One object of the present invention is the provision of a novel apparatus for processing metal work-pieces in such manner as to consistently obtain flawless pipes and tubes of the "seamless" type, and by the use of which the metal of the work-piece is processed in direct ratio to its plasticity.

Another object is to provide novel means for controlling the distortion, or "ovality", inherent in seamless pipe and tube methods in such manner as to completely avoid the possibility of flaws or defects in the processed work-piece.

A further object is the provision of a novel apparatus of the class described in which the

metal of the work-piece is diverted from a tangential path of travel, imposed by helically acting metal-working rolls, into a longitudinal direction, the diversion being exerted to a degree determined by the plasticity of the metal.

A still further object is to provide a novel means for automatically controlling the point of diversion in accordance with the temperature of various areas in successive, or single, work-pieces, 10 separate means compensating for the varying degrees of plasticity characteristic of different metals at the same temperature.

The foregoing and further objects of the invention will be apparent after referring to the 15 drawings, in which:

Figure 1 is a plan of the apparatus of the invention.

Figure 2 is a side elevation of a part thereof. 20 Figure 3 is a sectional elevation of part of the apparatus of Figure 1 as used in piercing operations.

Figure 4 is an elevation taken from the inlet end of the apparatus.

Figure 5 is an elevation on the line V—V of 25 Figure 1.

Figure 6 is an enlarged plan graphically representing the function of the apparatus.

Referring more particularly to the drawings, the numeral 2 designates a housing for part of 30 the apparatus of the invention. A pair of journals 3 are mounted on the housing 2 for rotatably supporting a pair of suitably driven shafts 4, each of which has secured to its end a conventional metal-working roll 5, such as is commonly used in the manufacture of seamless pipes and tubes.

The housing 2 is apertured in such manner as to provide machined ways above and below the metal-working rolls 5, as at 6 and 7, respectively. 40 A horizontally sliding block 8 is disposed in each of the machined ways 6 and 7, and is suitably apertured to provide a journal for rotatably supporting one end of a shaft 9. A grooved guide roll 10 is secured to the mid-portion of each of 45 the shafts 9 for rotation therewith.

The sliding blocks 8 are threaded, as at 8^a, to accommodate one of a pair of screws 12, which are provided with smooth extremities 12^a that are journaled in the housing 2 adjacent each of the 50 apertures of the ways 6 and 7.

A motor 14 is mounted adjacent the housing 2 and provided with a transmission unit 15, having a driven shaft 16, on which there is mounted a gear 17. The shaft 16 is adapted to drive the 55 lower of the shafts 9 through a drive shaft 18 and universal joints 19 and 20.

A shaft 21 is mounted above the transmission shaft 16 and carries a gear 22 which is in constant engagement with the gear 17. The shaft 60 21 is adapted to drive the upper of the shafts 9 in exact synchronism with its counterpart by means of a drive shaft 23 and universal joints 24 and 25.

A worm gear 26 is secured to one end of each 65 of the screws 12 and rotated by means of a co-operating worm 27, the latter being mounted on shafts 28 which are supported in bearings 29 that are associated with the housing 2. The lower of the shafts 28 carries a gear 30 while the 70 uppermost thereof carries a gear 31 which is in constant mesh therewith.

A motor 32 is mounted adjacent the gears 30 and 31 and is associated with a driven selective gear reduction transmission unit 33 which is 75 provided with a lever 34 for enabling the changing

of gears. The selective gear reduction unit 33 drives a shaft 35 to which there is secured a pinion 36 for rotating the gear 30 on the lower of the shafts 28.

A heat-responsive circuit making-and-breaking device, such as a photoelectric control unit, generally indicated at 37, is "trained" on a work-piece which is being processed at a point immediately before it is contacted by the metal-working rolls 5, and provides means for registering a relatively wide temperature range inherent in the work-piece at this point. The heat-responsive circuit making-and-breaking device 37 is operatively associated with a motor control unit 38, which is provided with any of the well known types of starting and stopping devices, limit relays, and reversing media, for automatically controlling the motor 32 in such manner as to enable the pinion 36 to move the contact areas of the grooved guide rolls 10 into exactly proper longitudinal position required by the temperature of the work-piece A, the function of the selective gear reduction transmission unit 33 being to further and adjustably modify this disposition in order to compensate for the varying degrees of plasticity characteristic of different metals at the same temperature.

If desired, the heat-responsive circuit making and breaking device 37 may be disconnected and the motor control box 38 actuated manually by 30 an operator who is in a position to closely observe the condition of the work-piece.

A piercing plug 39 is mounted on a mandrel bar 40 and disposed with its point at the approximate "gorge" of the metal-working pass.

In operation, the work-piece A, in the present instance a solid round or "billet" which is to be pierced, is introduced between the conventional metal-working rolls 5 where it is "necked down" 40 in accordance with the usual practice, to obtain a tendency of the central fibers of the metal to open preparatory to its being forced over the point of the piercing plug 39.

This "necking down" operation directs the 45 metal of the "billet" into vertical deformation, or "ovality", in addition to which a tendency toward elongation will be encountered. From the most constricted portion of the pass defined by the metal-working rolls 5, or what is known as 50 the "gorge", where the actual piercing occurs, this tendency toward "ovality" is much greater as the pierced "billet" or work-piece progresses through the outlet of the mill, and should be limited as much as possible in order to avoid 55 difficulties in the processed work-piece. Therefore, the function of the guide rolls 10 is to limit this injurious distortion and to divert successive increments of metal of the work-piece from circumferential travel, accruing from the processing 60 action of the metal-working rolls 5, into a longitudinal direction.

As hereinbefore stated, the metal of the work-piece is much more easily diverted into a longitudinal direction from a position adjacent the 65 outlet end of the mill, and this condition is particularly true if the work-piece is very highly heated, and therefore unusually plastic.

On the other hand, if the work-piece is not in 70 this preferred condition, due to insufficient heating, the contact surfaces of the guide rolls 10 should be closer to the "gorge" defined by the metal-working rolls 5 in order to limit the distortion at this point, as "tearing" would result 75

under these circumstances if the guide rolls were located at the outlet end of the pass.

In order to thoroughly, and automatically, compensate for these varying conditions inherent in single, or successive, work-pieces, the heat-responsive circuit making-and-breaking device, generally indicated at 37, actuates the devices of the motor control unit 38 for automatically starting, stopping, and reversing the operation of the motor 32 which functions through the selective gear reduction transmission unit 33 to properly position the guide rolls 10 longitudinally with respect to the metal-working rolls 5, the lever 34 being provided to compensate this operation in accordance with varying degrees of plasticity characteristic of different metals at the same temperature.

Referring to Figure 3 of the drawings, three longitudinal positions of the guide rolls 10 are disclosed relative to the piercing plug 39 which, of course, does not vary with respect to the positions of the metal working rolls 5. The line 10^a indicates a vertical line through the axis of rotation of the metal-working rolls 10 when they are disposed exactly at the "gorge" of the metal-working rolls, while the character A^a indicates in a dotted line the contact surfaces of the guide rolls while in this position. The line 10^b indicates the axis of rotation of the guide rolls 10 when they are positioned toward the outlet end of the pass, while the solid line A^b shows the contact surface of the guide rolls at this point. The line 10^c represents a line through the axis of rotation of the guide rolls when they are moved even further toward the outlet end of the pass, while the dotted line A^c indicates the contact areas of the guide rolls in this position.

Due to the operation of the various elements of the invention, the guide rolls 10 will limit the "ovality" of the work-piece A, and divert successive increments thereof from a circumferential to a longitudinal direction in direct proportion to the plasticity thereof, whereby excessive distortion is obviated and accordingly the usual imperfections resulting therefrom.

In a copending application, entitled Apparatus for processing metal work-pieces, filed October 9, 1933 Serial No. 692,875, I have described a method of regulating the longitudinal diversion of the metal by automatically varying the rate of rotation of the guide rolls.

In said application I claim the invention broadly in order to include the methods and devices of the present case, the claims of the latter being directed to distinguishable subject-matter.

It is to be understood that my invention is intended to cover any satisfactory secondary modifier for the final effect of the motor 32 on the longitudinal disposition of the guide rolls 10, in lieu of the selective gear reduction transmission unit 33; that the three positions for the guide rolls 10 are nominally illustrated, as any number thereof may be used; that any suitable heat-responsive circuit maker-and-breaker may be substituted for the suggested photoelectric control unit 37; that any other satisfactory means may be used for controlling the operation of the motor 32 in lieu of the devices mentioned to be associated with the motor control unit 38; and

that while I have shown and described one specific embodiment of the remainder of the invention I do not wish to be limited exactly thereto, since various modifications may be made without departing from the scope of my invention, 5 as defined in the following claims.

I claim:

1. Apparatus for processing tubular work-pieces comprising, in combination, a pair of power-actuated metal-working rolls, at least one guide 10 roll having its axis substantially at right angles with respect to the pass line defined by said metal-working rolls, means for rotating said guide roll with its periphery in contact with the work-piece, and means for regulating the longitudinal 15 disposition of said guide roll with respect to said metal-working rolls in accordance with the temperature of said work-piece, and secondary regulating means for further modifying the longitudinal disposition of said guide roll in accordance 20 with the resistance to displacement of the metal of the work-piece.

2. Apparatus for processing tubular work-pieces comprising, in combination, a pair of power-actuated metal-working rolls, at least one extraneous device for diverting successive increments of metal of the work-piece from a tangential into a longitudinal direction, means for automatically regulating the longitudinal disposition of said extraneous device in such manner 30 as to minimize the distortion of the work-piece, and secondary means for modifying the effect of said regulating means.

3. Apparatus for manufacturing pipes and tubes comprising a plurality of power-actuated 35 metal-working rolls, said metal-working rolls being constructed and arranged to move the work-piece longitudinally and work the material of which it is composed, whereby portions of the work-piece are caused to bulge intermediate the 40 metal-working rolls, at least one power-actuated guide roll disposed intermediate said metal-working rolls for limiting the bulging of the material of the work-piece and moving it longitudinally of its axis, in combination with means for 45 registering the temperature of the work-piece, and means operated by said temperature-registering means for moving said power-actuated guide roll axially with respect to the direction of longitudinal movement of the work-piece. 50

4. Apparatus for manufacturing pipes and tubes comprising a plurality of power-actuated metal-working rolls, said metal-working rolls being constructed and arranged to move the work-piece longitudinally and work the material of 55 which it is composed, whereby portions of the work-piece are caused to bulge intermediate the metal-working rolls, at least one power-actuated guide roll disposed intermediate said metal-working rolls for limiting the bulging of the material of the work-piece and moving it longitudinally of its axis, in combination with means for registering the temperature of the work-piece, means operated by said temperature-registering means for moving said power-actuated 60 guide roll axially with respect to the direction of longitudinal movement of the work-piece, and separate means for modifying the operation of 65 said last named means.
